UNITED STATES PATENT OFFICE.

A. H. WHITNEY, OF PORTLAND, MAINE.

IMPROVEMENT IN MEASURING-FUNNELS.

Specification forming part of Letters Patent No. **55,941**, dated June 26, 1866.

To all whom it may concern:

Be it known that I, A. H. WHITNEY, of Portland, in the county of Cumberland and State of Maine, have invented a new and useful Improvement in Funnel or Tunnels; and I hereby declare the following to be a full, clear, and exact description of the same, reference being made to the accompanying drawings, making part of this specification, in which—

Figure 1 shows a side perspective view of my invention; Fig. 2, a section of the same.

The object of my invention is the production of a funnel in which liquids can be retained for the purpose of being measured, in order to dispense with the employment of numerous measures of various sizes and capacities.

My invention consists in fitting a funnel with a stop-cock, by which the neck of the same can be closed; in marking upon the interior of the cone-shaped portion a scale, by which any desired quantity of liquid can be ascertained and measured; and in the combined use of certain other devices, hereinafter explained.

A represents a funnel having the stop-cock B fitted into the neck thereof, so that the neck can thereby be opened or closed at will.

F shows a form of a graduated scale to

measure any desired quantity of liquid in the funnel. C is a circular flange to enable the funnel to rest evenly and securely on the top of the neck of a bottle. D represents an air-vent to permit the free exit of the air as the bottle is filled.

By means of my invention the offices of a funnel to turn liquids into bottles or jugs and of measures to determine a certain amount are combined in a single article of much greater cheapness and convenience than those ordinarily employed for these purposes.

The handle H renders the funnel convenient when used as a measure.

I construct my invention of any of the materials usually employed in such articles. When made of glass a band of metal must be fitted around the neck for the purpose of securing the cock.

What I claim as my invention, and desire to secure by Letters Patent, is—

The combination, in a funnel, of the graduated scale, the stop-cock, the flange, and air-vent, all as and for the purposes specified.

A. H. WHITNEY.
